UNITED STATES PATENT OFFICE.

CLARENCE C. FAY, OF TOWER, MINNESOTA.

SELF-ADJUSTING FRICTION-BAND.

1,371,416.

Specification of Letters Patent.

Patented Mar. 15, 1921.

Application filed February 2, 1920. Serial No. 355,543.

To all whom it may concern:

Be it known that I, CLARENCE C. FAY, a citizen of the United States, residing at Tower, in the county of St. Louis and State 5 of Minnesota, have invented certain new and useful Improvements in Self-Adjusting Friction-Bands, of which the following is a specification, reference being had therein to the accompanying drawing.

10 This invention relates to automatic adjusting devices for friction bands and has special reference to bands such as are used in transmission devices for automobiles. The embodiment of the invention here shown and 15 described is particularly adapted for use in the transmission of a Ford automobile.

The principal object of the invention is to produce a practical automatic take-up device for bands of this character.

20 Other objects and advantages will appear in the further description of the invention.

In the accompanying drawings forming part of this application:

Figure 1 is an elevation of a fragmental 25 portion of a friction band viewed axially thereof.

Fig. 2 is an underside view of a fragmental portion of the normally stationary pilot lug, and

30 Fig. 3 is a similar view of a fragmental portion of the movable pilot lug and its pivotally connected dog.

The numeral 1 represents the band the normally operated end of which has rigidly 35 fixed thereto the pilot lug 2, and to the opposite end of the band is slidably attached the normally stationary pilot lug 3. These two lugs, in general appearance, are similar to those ordinarily found upon the three 40 brake bands in the transmission of a Ford car and are engaged and operate in all respects in the usual manner, by the pedal shaft 4, the lugs being normally separated by the expansive spiral spring 5, upon said 45 shaft.

The inwardly protruding hub 6 formed integral with the transmission housing forms an abutment for the pilot lug 3 and the reciprocal motion of the pedal shaft 4 is 50 what operates the opposite end of the band together with the counteracting motion of the spring 5.

In my improved structure the band 1 is slidably attached to the lug 3, there being 55 slotted holes 7 and 8 provided for the rivets 9 and 10 respectively, which latter are rig-

idly carried by the band, and under the head of the rivet 10 is an expansive flat spring 12 the ends of which impinge against the back of the lug and normally hold the band in 60 engagement with the inner face of the lug.

The inner face of the lug 3 has a cut-away portion 13 across its entire face and also has a central cut-out portion 14, which bifurcates the under face of the lug to a circumferential depth somewhat greater than the width of the upstanding bifurcated portion of the lug. On either side of the cut-away portion or slot 14 the lower terminations of the upstanding portions of the lug are serrated or provided with teeth as at 15 so that there are two series of teeth, one upon either side of the slot 14, and the cut-away portion 13 is simply to provide clearance for the transversely toothed section 16 of the end of 70 the band, and portions of which teeth normally register with the toothed sections 15 of the lug.

The toothed section 16 of the band is preferably made to extend past the inner face 80 of the upstanding bifurcated portion of the lug 3, toward the lug 2, when the inner termination of the toothed section abuts the lower termination of the cut away portion 13, such arrangement of parts providing ample room for ultimate adjustment of the 85 band.

At the base of the bifurcated upstanding portion of the pilot lug 2 are formed two inwardly projecting lugs 17, the space intermediate of said lugs being cut away beneath the upstanding portions of the pilot lug 2 as at 18 so as to give clearance for the adjacent end of the dog 19 which is pivotally mounted intermediate of the lug 17 as at 20, 95 said pivotal end of the dog being provided with a slotted hole 21 surrounding the pivot-pin 20. The free end of the dog reaches across the gap intermediate of the two pilot lugs of the band, and extends within the entrance to the slot 14, it having provided upon the end thereof a series of preferably seven or eight teeth, which normally engage the exposed teeth on the end of the band, within the slot 14. To insure such engagement of 105 the dog 19 a depressive flat leaf spring 22 of any desired form is attached in any convenient manner within the slot 14, to maintain a downward pressure upon the head of the dog.

The device operates as follows:

The band having first been positioned

about the drum to which it is engaged, the dog 19 when forced into the mouth of the slot 14 by the bringing together of the pilot lugs 2 and 3, will immediately engage the 5 foremost teeth upon the band and there normally hold the ends of the band in such position until the coöperative parts such as the pedal shaft, etc., are applied, thus avoiding the necessity of wiring or lashing the 10 pilots together otherwise, as is commonly practised with the ordinary band, and considered somewhat of an annoyance. Then after the pedal shaft is applied and service commenced, the band will operate just as 15 usual by the reciprocation of said shaft until, peradventure, the lining of the band becomes sufficiently worn to allow the pin 20, during its reciprocal motion, to forcibly engage the farthest termination of the slot 20 21 in the dog 19, upon its outward stroke. When the dog is thus engaged sufficiently it will reach forward, into the slot 14 of the opposite pilot, and be advanced enough to engage one more notch in the band, then 25 when the pilot lug 2 is released to its full return stroke the pin 20 will be found to engage the opposite or inner end of the slot 21 and tend, by the action of the spring 5, to draw the dog 19 back home to its original 30 position. This action will, as is obvious, pull the opposite end of the band a distance equal to what was gained by the end of the dog, to wit., one notch of the relation between the end of the band and the toothed 35 portions 15 of the pilot block 3, thus shortening the band just one notch where it may continue in service until sufficiently worn to make another similar contraction as above described.

40 This advancement of the band in relation to the pilot block 3 makes evident the necessity of the slotted holes 7 and 8 for the rivets 9 and 10 which will permit them to creep up on the pilot block as the band advances, 45 furthermore the serrated end 16 of the band having to spring away from the face of the

block 3 slightly in its advancement, makes manifest the advantage of the spring 12 under the head of the rivet 10 to permit of such resilient action and still hold the 50 band snugly against the face of the pilot block.

From the foregoing it is evident that I have devised a simple practical and efficient automatic take-up for friction bands the 55 specific structure of which as herein described may be considerably departed from without affecting the scope of the appended claims.

What I claim is:

1. The combination with a brake band of the character described having reciprocable means coöperatively engaged therewith for applying and releasing the band, of interlocking coöperative means carried by 60 the ends of the band, for the purpose described.

2. The combination with a brake band of the character described having reciprocable means coöperatively engaged therewith for 70 applying and releasing the band, of reciprocable means carried upon one end of the band and fixed means upon the opposite end of the band coöperatively engageable by said last mentioned reciprocal means substantially as and for the purpose described.

3. The combination with a brake band of the character described having reciprocable means in coöperative relation therewith for applying and releasing the band, of means 80 carried upon one end of the band for engagement with the opposite end thereof, means upon said last mentioned end for coöperative engagement with the means carried upon the other end.

In testimony whereof I hereunto affix my signature in the presence of two witnesses.

CLARENCE C. FAY.
